(57) **CLAIM**

The ornamental design for a coffee brewer tray and bonnet, as shown and described.

DESCRIPTION

FIG. 1 is a top perspective view of a coffee brewer tray and bonnet showing my new design;

FIG. 2 is a top plan view, in enlarged scale, thereof;

FIG. 3 is a bottom plan view, in enlarged scale, thereof;

FIG. 4 is a front elevational view, in enlarged scale, thereof; FIG. 5 is a sectional view thereof taken along line 5—5 of FIG. 2.

FIG. 6 is a right-hand side view, in enlarged scale, thereof; and,

FIG. 7 is a left-hand side view, in enlarged scale, thereof. The broken lines in FIG. 1 are for illustrative purposes only and form no part of the claimed design.
